INVENTOR

BY *E. M. Nixon.*

ATTORNEY.

UNITED STATES PATENT OFFICE.

MOSES C. NIXON, OF OMAHA, NEBRASKA.

BALING-PRESS.

SPECIFICATION forming part of Letters Patent No. 515,786, dated March 6, 1894.

Application filed January 10, 1893. Serial No. 457,935. (No model.)

To all whom it may concern:

Be it known that I, MOSES C. NIXON, of Omaha, in the county of Douglas and State of Nebraska, have invented certain useful Improvements in Baling-Presses; and I do hereby declare that the following is a full, clear, and exact description of the invention, such as will enable others skilled in the art to which it appertains to make and use the same, reference being had to the accompanying drawings, which form a part of this specification.

This invention has relation to a new and novel hay press.

The object of this invention is, to provide a hay press that shall be simple of construction and positive in its operation.

In the accompanying drawings, Figure 1 shows a side elevation partly in section of a press embodying my invention. Fig. 2 is a top view thereof in section. Fig. 3 shows the head plate as closed upon the plunger head. Fig. 4 is an end view of Fig. 3. Fig. 5 is an end view of the anchor block; Fig. 6 a front view thereof. Fig. 7 is a side view of the toggle arm, while Fig. 8 shows a side elevation of the power arm.

A represents a supporting standard provided with a hopper A'.

A'' is a plunger head which reciprocates within the press, provided with the ears a', a', adapted to support the end of the plunger bar B. Secured to the plunger head is an angle bar b, provided with an opening through which the rods b' pass, and so secures the sliding head plates c, one end of which is bent downward and slides upon the top of the plunger, the rod b' bending up and being secured to the lower portion of the plate c. This plate projects upon each side beyond the head as will be understood by referring to Fig. 4, the projecting edges working within slots c' of the standard A, as may be seen by referring to Fig. 1.

Secured between the ears a' is the bifurcated link d, between which the plunger bar B is adjustably secured, by means of the bolts e, e, which are secured to the bar B and permitted to slide within a central slot of the link d, so that any desirable adjustment may be obtained. At the remaining end the bar B is secured to the bifurcated free end of the serrated toggle arm D, which is provided upon

one side with the teeth d'. This arm is pivotally secured to the anchor block E, which is provided with the ear e' which secures the toggle D. This block E is further provided with the bearing e'' and the semi-circular track portion g.

Working upon the bearing portion e'' is the power bar F which is fixed upon the shaft h' and is provided with the oval serrated head h adapted to successively engage the serrations of the arm D, the vertical power shaft h' and the rolls 1, 2. Above, the shaft h' is provided with the operating bar k. To give support to the arm D, I provide the supporting roll k' which is adapted to work upon the semi-circular track portion g.

The parts having all been properly constructed and arranged, the operation of my device would be as follows: If the parts were positioned as shown in Figs. 1 and 2 for instance, as the operating bar k was turned, the toggle arm would be carried backward by the serrations or teeth upon the head of the power bar F, so as to carry the plunger head backward into its other extreme position, in the direction indicated by the arrow x in Fig. 2. The roll 2 of the revolving power bar F would then collide with the toggle arm D, and so again force it into the position shown in Fig. 2. The bar F is continuously revolved and actuates the plunger twice during each revolution. The sliding head plate c, as the plunger would be carried forward, extends as shown in Fig. 1, so as to close the hopper opening and prevent any hay from passing into the press at the rear of the plunger head. In passing into its rear position, the plunger head would carry the head plate with it so as to clear the hopper opening, the plate doubling upon the head, as shown in Fig. 3.

Having thus described my invention, what I claim as new, and desire to secure by United States Letters Patent, is—

1. In a hay press, the combination with a supporting standard, of a plunger head and bar, a sliding head plate movably secured to the plunger head, adapted to open and close the hopper opening of said press, in combination with suitable operating mechanism, all substantially as and for the purpose set forth.

2. In a hay press, the combination with a supporting standard, of a plunger head and

bar, an anchor block provided with a projecting ear and a semi-circular track, a serrated toggle arm secured to said plunger bar, and movably held upon said anchor block, a vertical shaft mounted adjoining said toggle arm, and provided with a power bar, said bar having a serrated oval head and two terminal rolls, said serrated head being adapted to engage the serrated toggle arm in carrying said arm in one direction and said rolls engaging said toggle arm in carrying said arm in the opposite direction, all substantially as and for the purpose set forth.

3. In a hay press, the combination with the standard A, of the plunger head A'', the plunger bar B connected to said head, the anchor

block E provided with the ear e' and the bearing e'', the serrated toggle arm D working between said block E and ear e' and connected to said bar B, the power bar F provided with the serrated head h meshing with the arm D, and provided with the rolls 1 and 2, and the power shaft h', all arranged to operate substantially as and for the purpose set forth. 25

In testimony whereof I affix my signature in presence of two witnesses.

MOSES C. NIXON.
